UNITED STATES PATENT OFFICE

JAMES P. MCCREADY, OF BERLIN, NEW HAMPSHIRE

VALVE LIFTER

Application filed January 15, 1930. Serial No. 421,026.

This invention relates to a spring valve lifter or compressor, the general object of the invention being to provide a strong, efficient tool having double jaws, with means whereby the parts are automatically locked in any position when under the pressure of a valve spring, thus leaving the operator's hands free to extract the pin or catch in the valve stem, the tool providing a strong, accurate check, allowing springs to be compressed easily and distance measured more accurately than can be performed by the forms of spring lifters using a spring for adjustment.

The jaws are so constructed that in compressing the valve springs, they always remain on an even angle, no matter to what height they are compressed, and the weight of the springs acts as a lock for the jaws.

This invention also consists in certain other features of construction and in the combination and arrangement of the several parts, to be hereinafter fully described, illustrated in the accompanying drawings and specifically pointed out in the appended claims.

In describing the invention in detail, reference will be had to the accompanying drawings wherein like characters denote like or corresponding parts throughout the several views, and in which:

Figure 1 is an elevation showing the device in use.

Figure 2 is a top plan view of the device.

Figure 3 is an elevation showing the parts in a position to compress a spring.

Figure 4 is a section on line 4—4 of Figure 1.

Figure 5 is a detail view of one of the jaws.

Figure 6 is a view of another form of jaw.

Figure 7 is a view of another form of jaw.

In these views, the numeral 1 indicates the lower handle and 2 the upper handle. Both of these handles are formed of metal strips bent into open loop shape, with the inwardly extending lips 3 on the ends of the lower handle providing rests for engaging a part of the valve assembly. The ends of the limbs of the upper handle extend downwardly and forwardly and are formed with the slots 4. These limbs are close enough together to pass between the limbs of the member 1. An up-

right 5 is fastened to each limb of the lower handle 1 an appreciable distance from the end of the limb, each upright being set a little beyond right angles to the lower handle and a pivot bolt 6 passes through the upper ends of the uprights and through the limbs of the upper handle a slight distance in rear of the ends of the slots 4 so that the upper handle is pivotally supported from the lower handle.

A jaw member 5, composed of the two parts 5', is pivoted to the outer faces of the uprights 5 by the bolt 6, and the free ends of the two parts 5' are tapered and formed with the inwardly extending lips 5'', each lip having an upright part at its rear end.

Each part 5' is formed with a depending part 7 at its rear which has a slot 8 therein.

A roller 11 passes through the slots 4 in the handle 2 and through the slots 8 in parts 7. A disk 12 is connected with each end of the roller, one disk being threaded to the end of the roller. These disks engage the outer faces of the jaw parts and serve to guide the roller as it works back and forth so that the roller is always held at right angles to the handles and prevents any chance of the roller jamming or becoming caught. As the roller passes through the slots 8, the jaw member is raised and lowered by the roller as the upper handle 2 is raised and lowered and said roller acts as a lock to hold the jaw member in position by the pressure of the valve spring when the parts are in a position holding the spring compressed. A rod 9 passes through holes in the parts 5' and a spring 10 is arranged on the rod and tends to press the parts 5' apart and prevents the jaw parts from tilting when the device is turned upside down.

As will be understood, the upper handle is raised to the position it occupies in Figure 1 to lower the jaw member and then the parts are placed under a spring. The upper handle is then lowered and as this is being done, the roller will raise the jaw member and thus compress the spring. By placing the ends of the roller in the slots, the roller will permit the jaw member to move to varying degrees and will lock the jaw.

member in its final position when the handle 2 is in adjusted position.

The jaw members shown in Figures 3 and 5 are designed for use with the ordinary type 5 of L type motors and when the device is to be used on the valves of continental motors of the L type, a jaw member, formed of the jaw parts 11 shown in Figure 6, is substituted for the other jaw member. This jaw 10 part has its lip 12' formed with front and rear projections 13.

In order to substitute one jaw member for another the bolt 6 and the roller 7 are removed by removing the nuts from these 15 members and then the jaw member is removed and the other jaw member put in its place, after which the bolt 6 and the roller 7 are replaced to hold the second jaw member in position.

20 Figure 7 shows another form of jaw member, which has a U-shaped plate 14 connected with its jaw parts. The rear end of the U-shaped plate has a lip 15 formed thereon. The front ends of this plate and 25 the front ends of the lips of the other forms are beveled, as shown, so they can readily pass under the springs. The jaw member is used with other forms of L type motors.

30 As before stated, this device forms an efficient tool for the compression of valve springs, and the parts are held in adjusted position with the spring lifted by the arrangement of the roller and slots so that it 35 is not necessary to hold the tool after it has been adjusted to lift the spring. The spring acts as a lock for the jaws and the jaws are so constructed as to always remain on an even angle.

40 It is thought from the foregoing description that the advantages and novel features of the invention will be readily apparent.

It is to be understood that changes may be made in the construction and in the combination and arrangement of the several 45 parts, provided that such changes fall within the scope of the appended claims.

What I claim is:—

1. A device of the class described comprising upper and lower handles, an upright 50 fastened to the lower handle intermediate its ends and to which the upper handle is pivoted an appreciable distance from one end, this end of the upper handle having slots 55 therein, a roller having its ends passing through the slots, a jaw member pivoted to the uprights and having a slot therein through which the roller passes.

2. A device of the class described comprising upper and lower arms, each formed 60 of a strip of material bent into loop shape, uprights connected with the limbs of the lower arm intermediate the ends thereof, a pin passing through the upper ends of the uprights 65 and through the limbs of the upper handle

an appreciable distance from the extremities of the limbs, said extremities having slots 70 therein, a roller having its ends passing through the slots, washers on the ends of the rollers, a jaw member composed of two members pivoted to the upper ends of the uprights, the free ends of said members having spring 75 engaging parts thereon, said members being slotted with the roller passing through the slots.

3. A device of the class described comprising upper and lower arms, each formed of a strip of material bent into loop shape, uprights connected with the limbs of the lower arm intermediate the ends thereof, a pin passing through the upper ends of the uprights and through the limbs of the upper handle an appreciable distance from the extremities of the limbs, said extremities having 80 slots therein, a roller having its ends passing through the slots, washers on the ends of the rollers, a jaw member composed of two members pivoted to the upper ends of the uprights, the free ends of said members having spring 85 engaging parts thereon and said members being slotted to receive the roller and means whereby other jaw members may be substituted for the first member.

4. A device of the class described comprising upper and lower arms, each formed of a strip of material bent into loop shape, uprights connected with the limbs of the lower arm intermediate the ends thereof, a pin passing through the upper ends of the uprights and through the limbs of the upper handle an appreciable distance from the extremities of the limbs, said extremities having 90 slots therein, a roller having its ends passing through the slots, washers on the ends of the rollers, a jaw member composed of two members pivoted to the upper ends of the uprights, the free ends of said members having spring 95 engaging parts thereon, said members being slotted with the roller passing through the slots and spring means for frictionally holding the jaw member against free 100 movement.

In testimony whereof I affix my signature.

JAMES P. McCREADY.
